TABLE FOR ROLLING MILLS

Ernest Drexler, Pittsburgh, Pa.

Application June 23, 1932, Serial No. 618,850

3 Claims. (Cl. 80—47)

This invention, described and claimed in part in my prior patent, No. 2,001,129 of May 14, 1935 relates to tables for rolling mills of any of the known types requiring entry or delivery tables for the purpose of reversing the direction of travel of the material to re-enter the same between the working rolls of the mill when it is desired, for example, to further reduce the thickness of the material or to obtain a smoother finish or greater hardness thereof.

A rolling mill table usually comprises a series of rollers journaled for rotation and driven either by miter gears and line shafts, worms and worm wheels, chains and sprockets, cranks and connecting rods, or by individual coupled motors.

In all cases it is necessary to reverse the direction of rotation of the roller driving means when a change in the direction of travel of the material is desired. This requires time, and as a consequence, if frequent reversals are effected, the output of the mill is considerably diminished. In addition, there is the inherent disadvantage of the table mechanism being subjected to stresses and strains and excessive wear due to the starting, stopping and reversing of the direction of rotation of the rollers. Especially is this true in respect to the reversible electric motors and related gear reduction units which comprise the most common means of driving the rollers, motors of special and expensive construction being required to withstand frequent reversals without overheating. Furthermore, the common practice heretofore has been to pivot the tables at their ends remote from the rolls and to tilt the ends of the tables nearer the rolls upwardly so that reversal of the direction of rotation of the rolls is effective to convey the material over the rolls for re-entry between the same. This, however, has the disadvantage, especially in the case of the rolling of light weight, smooth surfaced materials, that considerable slippage between the material and the conveyor rollers occurs, the material, due to insufficient traction and under the influence of gravity tending to slide down the inclined table away from the mill rolls instead of being conveyed over the same. Consequently, the services of an attendant stationed at the table to push the material upwardly over the table are required.

Accordingly, the general object of the present invention is to provide a relatively simple, thoroughly practical table for rolling mills embodying a construction and mode of operation whereby the foregoing and other disadvantages inherent to rolling mill tables of prior types are eliminated.

With the foregoing and other objects in view, which will become more fully apparent as the nature of the invention is better understood, the same consists in the novel features of construction, combination and arrangement of parts as will be hereinafter more fully described, illustrated in the accompanying drawings and defined in the appended claims.

In the drawings, wherein like characters of reference denote corresponding parts in the different related views:

Figure 1 is a top plan view of a rolling mill equipped with tables constructed in accordance with one practical embodiment of the invention.

Figure 2 is a side elevation of the mechanism 15 illustrated in Figure 1, showing one of the tables in longitudinal section.

Figure 3 is an end elevation of the mechanism shown in Figures 1 and 2.

Figure 4 is an enlarged transverse section 20 through one of the tables showing the vertically movable set of rollers in an elevated position.

Figure 5 is an enlarged horizontal section taken approximately on the line 5—5 of Figure 2.

Figure 6 is a detail sectional view through the 25 clutch device for effecting elevation and permitting lowering of the movable sets of rollers of the tables.

Figure 7 is a top plan view illustrating chain conveyor elements which may be used in lieu of 30 the rollers illustrated in Figures 1 to 5; and

Figure 8 is a side elevation of the structure illustrated in Figure 7 and showing by dotted lines the vertically movable chain conveyor in elevated position.

Referring to the drawings in detail, first to the practical embodiment of the invention illustrated in Figures 1 to 6, A designates, generally, the usual housing of a sheet or plate hot mill having journaled therein the usual super-imposed rolls 40 a, a. In the present instance separate conveyor tables constructed in accordance with the invention and designated generally as B, B' are illustrated as being disposed, one at the entering side and the other at the delivery side of the rolls, for respectively conveying the sheets or other material to and from the rolls. This is a preferred arrangement inasmuch as the tables thus arranged are adapted for cooperation with each other to effect repeated passes of the material between the rolls. However, the respective tables are entirely separate and distinct from each other and either may be used to the exclusion of the other. Moreover, the tables are, or may be, 55

duplicates of each other and therefore a description of one will suffice for both.

Accordingly, and selecting for purposes of this description the table B disposed at the entering side of the mill rolls *a*, it will be observed that said table is inclusive of a frame or carriage 10 provided with grooved supporting wheels 11 resting on track rails 12 of inverted V-shaped section whereby the carriage is supported and guided 10 for movement bodily towards and away from the rolls *a*.

The carriage 10 is composed of a pair of side rails 13 connected together by transverse members 14 and constitutes a carrier for a set of transverse rollers 15 which are suitably journaled at their ends in said side rails. All of the rollers 15 are of the same diameter and, as shown, they are disposed in a common horizontal plane to properly support and convey 20 a sheet of material resting thereon. They are to be driven in unison in any suitable or desired manner, as, for example, by means of an electric motor individual to each roller and contained therein as shown, for instance, in my Patent 1,889,174 and as indicated by dotted lines in Figure 4 of the drawings. During operation of the table the carriage 10 is to be held against movement along the track rails 12. Accordingly, as illustrated in Figure 4 a simple yet effective 25 means of accomplishing this purpose comprises clamp bolts 16 depending from the axle 17 of a pair of the wheels 11 or from one of the cross members for clamping engagement with portions of the track rails 12.

30 In addition to the carriage 10 with its rollers 15 the table includes a vertically movable frame 18 composed of a pair of side rails 19 connected together by cross members 20 and carrying, as in the case of the carriage 10, a set of transverse rollers 21, the side rails 19 of said frame 18 being disposed outwardly of the side rails 13 of the carriage 10 and having the ends of the rollers 21 journaled therein.

As in the case of the rollers 15 of the carriage 45 10, the rollers 21 of the frame 18 all are of the same diameter and are driven in any suitable manner as, for example, by means of individual motors mounted therein.

The rollers 15 of the carriage 10 all rotate in 50 a direction to advance sheets or other material disposed thereon towards the rolls *a*, while the rollers 21 of the frame 18 all rotate in the opposite direction. During the normal operation of the mill the rollers 21 are disposed suitably below the rollers 15 so that the sheets or other material rest upon and are moved only by the latter rollers. On the other hand, when it is desired to reverse the direction of travel of the material, the frame 18 is elevated to dispose the rollers 60 21 thereof above the rollers 15 so that only the rollers 21 are effective to move the material.

The means mounting the frame 18 for vertical movement comprises a base 22 suitably mounted in a fixed position below the track rails 12 and having suitably guided therein for vertical movement a carrier 23 which is forked at its upper end to provide arms 24 to which the side rails 19 of the said frame are detachably connected as indicated at 25. The carrier 23 is provided with a 70 rack 26 with which meshes a pinion 27 fixed to a horizontal shaft 28 journaled in the base 22. Thus, by rotation of the shaft 28 in one direction the carrier 23, and with it the frame 18, is elevated. On the other hand, due to the weight of 75 the carrier 23 and the frame 18, said carrier

and frame gravitate to a normal lowermost position in which the rollers 21 are disposed below the rollers 15 whenever free rotation of the shaft 28 is permitted. In this connection it will be observed that the side rails 13 of the carriage 10 are provided with recesses opening through their upper edges to accommodate the preferably reduced ends of the rollers 21 and the cross members 20 thereby to permit said rollers 21 to move downwardly below the rollers 15. 10

In view of the foregoing the general mode of operation of the tables B, B' will be apparent. Normally the rollers 21 of both tables are disposed below their related rollers 15 and only the latter rollers are effective to support and move 15 the material, the said rollers 15 of both tables B, B' rotating in the same direction whereby the material is advanced by the rollers 15 of the table B at the entrance side of the rolls *a* and is removed from the rolls by the rollers 15 of the table 20 B' at the delivery side of the rolls. Assuming now that it is desired to return a rolled sheet or the like from the table B' to the table B to again be passed between the rolls *a*, the operation consists simply in elevating the frames 18 25 of the respective tables to dispose the rollers 21 of the tables suitably above the rollers 15. The sheet or the like thus is picked up and elevated by the rollers 21 and, due to the direction of rotation of the rollers 21 being counter to the 30 direction of the rollers 15, the elevated sheet is moved by the rollers 21 of the table B' towards the rolls *a*. The amount of elevation of the rollers 21 is such that the sheet may pass over the rolls *a* onto the rollers 21 of the table B, and when this occurs the frames 18 of the respective tables are lowered to deposit the sheet on the rollers 15 of the table B whereby the sheet again is advanced by the latter rollers to and between the rolls *a*. In this connection, different types of 40 mills may require different amounts of elevation of the rollers 21, but the present manner of mounting the rollers 21 obviously provides for obtaining any desired amount of elevation of 45 said rollers within practicable limits.

Side guards 29 are provided to guide the sheets or the like in their movement over the tables, and in this connection a feature of the invention resides in so mounting said side guards that they not only are adjustable to accommodate there- 50 between sheets or the like of different widths, but are effective to guide the sheets whether the same are resting on the rollers 15 or on the elevated rollers 21.

The side guards 29 are in the form of longitudinal plates disposed, one at each side of the frame 18 and mounted, respectively, on the inner ends 30 of levers 31 which are pivoted intermediately in brackets 32 carried by the side rails 19 of said frame 18. The other or outer ends 33 of said levers extend downwardly and outwardly and are connected together by a link or rod 34. Thus, by longitudinal movement of the respective rods 34 the levers 31 are swingable in unison to move the guard plates either inwardly or outwardly. In this connection any suitable means may be provided to hold the plates in a desired adjusted position, such means being illustrated in the present instance as comprising a bracket 35 for each link or rod 34 fixed to the related side rail 19 of the frame 18 and having the related link or rod slidably engaged therewith, the bracket having an opening for alignment with any one of a number of openings 75

in the link or rod for the reception of a suitable pin or keeper 36.

Special and novel means are provided for elevating and permitting lowering of the frames 18 of the tables B, B' in unison. On corresponding ends of the shafts 28 are fixed bevel gears 37 which mesh with similar gears 38 fixed on a shaft 39, the pairs of gears 37, 38 being disposed preferably within suitable housings 40 in which the shaft 39 is journaled. Alined with the shaft 39 is a shaft 41 having fixed thereto a worm wheel 42 with which meshes a worm 43 on the shaft of a driving motor 44. Adjacent ends of the shafts 39 and 41 have fixed thereto bevel gears 45 and 46, respectively, which mesh with other bevel gears 47 journaled in a housing 48 mounted for rotation about the common axis of the shafts 39, 41. The gears 45, 46 and 47, together with the housing 48, obviously constitute a differential gear connection between the shafts 39, 41 operable either to transmit power from the shaft 41 to the shaft 39 for the purpose of rotating the shafts 28 to raise the frames 18, or to permit the shafts 28, 39 to rotate under the influence of the weight of the frames 18 and their carriers 23, thereby to permit said frames and carriers to gravitate to their lowermost positions with the rollers 21 disposed below the rollers 15 while the motor 44 continues to operate and drives the shaft 41 in a single direction. In other words, assuming continuous rotation of the motor and consequent continuous rotation of the shaft 41, it is manifest that if the differential gear housing 48 is held against rotation the gear 46 will drive the gears 47 and the latter gears will drive the gear 45, thereby imparting rotation to the shaft 39 and the shafts 28. In this connection it is understood, of course, that the direction of rotation of the motor 44 is such as to rotate the shafts 28 in a direction to elevate the frames 18. Now, on the other hand, when the gear housing 48 is not held against rotation, it is apparent that the gears 47 may rotate with the housing about the gear 45 without imparting motion to the shaft 39, and this being true it follows that when the frames are in an elevated position and the housing 48 is not held against rotation the shaft 39 is free to turn to permit the frames to gravitate to their lowermost positions, despite continued rotation of the shaft 41 by the motor.

A practical means of releasably holding the gear housing 48 against rotation is illustrated in Figures 1, 3 and 6 of the drawings and comprises a pair of arms 49 pivoted to a suitable fixed support 50 for swinging movement towards and away from the housing and carrying brake elements 51 for engagement with the housing. A bell-crank lever 52 is pivoted to the free end of one of the arms 49 and is connected at one end to the free end of the other of the arms 49 by a link 53 and at its other end is connected by a link 54 with an intermediate portion of a pivoted lever 55 having connected therewith a solenoid core 56 operating within a solenoid winding 57. The lever 55 is weighted and is so disposed as to normally operate through its connection with the arms 49 to urge them inwardly to braking positions relative to the housing 48. On the other hand, the solenoid comprising the core 56 and the winding 57 is so disposed as to swing the lever 55 in a direction to move the arms outwardly into non-braking relationship to the housing 48 when the winding 57 is energized.

As illustrated in Figure 6 of the drawings, a foot

operable switch 58 may be provided in the solenoid circuit for opening and closing the circuit to respectively release and hold the housing 48. Because of this arrangement it is believed to be clear that simply by opening the solenoid circuit the frames 18 will be elevated and by closing said circuit the frames are permitted to gravitate to their lowered positions, while the motor 44 continues to operate in a single direction. Thus, provision obviously is made for quickly returning any sheet or the like from the table B' to the table B for re-entry between the rolls a without reversing the direction of rotation of any of the rollers 15 or 21.

As aforesaid, the rollers 15 and 21 preferably are driven by individual electric motors, and in this connection, in order to provide current of desired frequency for operating said motors, a generator 59 preferably is belted or otherwise suitably connected with the motor 44 to be driven thereby.

As illustrated in Figure 2 of the drawings, bumper springs 60 or suitable equivalents thereof, such as pneumatic devices, preferably are provided to cushion the carriers 23 for the frames 18 at the ends of the up and down movements of said carriers.

Due to the detachable connections 25 between the frames 18 and their carriers 23 said frames may at any time be disconnected from said carriers to be deposited on the carriage 10 for transportation by the latter along the track rails 12 either to clear the mill or for any other desired purpose.

While rollers preferably are employed as supporting and conveying means for the sheets or the like the use of rollers for this purpose obviously is not essential. On the contrary, any equivalents of the rollers 15 and 21 may be employed in lieu thereof. For example, referring particularly to Figures 7 and 8 of the drawings, it will be observed that the supporting and conveying means for the material may comprise endless chains 61 operating over sprocket wheels 62 at the ends of the carriage 10' and the frame 18', respectively. For driving the chains the sprocket wheels at one end of both the carriage 10' and the frame 18' may be carried by a hollow member 63 equipped in the same manner as the rollers 15 and 21 with a motor for rotating the same.

From the foregoing description considered in connection with the accompanying drawings it is believed that the construction, operation and advantages of the invention will be readily understood. It is desired to point out, however, that while specific structural embodiments of the invention have been illustrated and described, the invention nevertheless is readily capable of embodiment in various other mechanical structures within the spirit and the scope thereof as defined in the appended claims.

I claim:

1. A table for rolling mills comprising a constantly horizontally disposed material supporting and conveying element, means for driving said element continuously in a single direction, a second constantly horizontally disposed material supporting and conveying element mounted for vertical movement above and below the first mentioned conveyor element and disposed so that when elevated it is effective to lift material off the first mentioned conveyor element, means for driving said second mentioned conveyor element continuously in a direction opposite to the first

- mentioned conveyor element, power means rotating continuously in a single direction for elevating said second mentioned conveyor element from a position below to a position above the first mentioned conveyor element, and a connection between said power means and said second mentioned conveyor whereby during continued rotation of said power means said conveyor element may be permitted to gravitate to a position below said first mentioned conveyor element.
2. In a rolling mill, in combination with mill rolls, separate tables at the entering and the delivery sides of the rolls, each table being inclusive of two interdigital material supporting and conveying elements, means for moving the conveying elements of each table in opposite directions, respectively, to convey the material in opposite directions, one element of each table being mounted for vertical movement above and below the other whereby either element may be caused to constitute the effective material supporting and conveying element, a single continuously operating motor, and a connection between said motor and the vertically movable elements of both tables including means whereby the motor may be made effective to elevate said vertically mov-

able elements in unison and whereby said vertically movable elements may be lowered while the motor continues to operate in a single direction.

3. In a rolling mill, in combination with mill rolls, separate tables at the entering and the delivery sides of the rolls, each table being inclusive of two interdigital material supporting and conveying elements, means for driving the conveying elements of each table continuously in opposite directions, respectively, to convey the material in opposite directions, one element of each table being mounted for vertical movement above and below the other whereby either element may be caused to constitute the effective material supporting and conveying element, a single continuously operating motor and a differential gear connection between said motor and the vertically movable elements of both tables whereby the motor may be made effective to elevate said vertically movable elements in unison and whereby said vertically movable elements may be lowered while the motor continues to operate in a single direction.

ERNEST DREXLER.
